H. A. Estes.
Horse Hay-Fork.
N° 74064

Patented Feb. 4, 1868

Attest,
J. McConomy
G. W. Reed

H. A. Estes

United States Patent Office.

HENRY A. ESTES, OF JERSEY CITY, NEW JERSEY, ASSIGNOR TO HIMSELF
AND GEORGE SMITH, OF SAME PLACE.

Letters Patent No. 74,064, dated February 4, 1868; antedated January 31, 1868.

IMPROVEMENT IN HORSE HAY-FORKS.

The Schedule referred to in these Letters Patent and making part of the same.

TO ALL WHOM IT MAY CONCERN:

Be it known that I, HENRY A. ESTES, of Jersey City, in the county of Hudson, and State of New Jersey, have invented certain new and useful Improvements in Hay-Elevators; and I do hereby declare that the following is a full, clear, and exact description of the same, reference being had to the accompanying drawings making a portion of this specification, in which—

Figure 1 is a side view of a hay-elevator, constructed according to my invention, showing the same in a closed position.

Figure 2 is an edge view of the same in a like position.

Figure 3 is a central vertical section of the same in the open position in which the same is used in raising the hay.

Similar letters of reference indicate corresponding parts in all the figures.

This invention relates to that class of horse hay-elevators commonly known as harpoon-forks, and it consists in a toggle-joint and central operating-rod, in combination with a tubular shaft and laterally-moving lifting-spurs, whereby the said spurs may be readily brought to and retained in a position at right angles to the aforesaid shaft, in order to lift the hay, or be conveniently tripped or operated to release and drop the same therefrom when raised to the height desired.

The invention further consists in a guard, so arranged at the upper end of the shaft mentioned, and in relation with a lever, which operates the central rod and the lifting-spurs, that the said lever is effectually prevented from striking against and being injured by beams, or similar obstructions, when the apparatus is employed in barns or buildings.

The invention further consists in a novel arrangement of parts, whereby the apparatus, as a whole, is made of very compact and convenient form, and capable of being very conveniently manipulated when in use.

To enable others to understand the construction and operation of my invention, I will proceed to describe it with reference to the drawings.

A represents the stock or main portion of the fork, which may be of cast iron or other suitable material, and which is made hollow or of tubular form, as shown in fig. 1, and preferably with flattened sides, as indicated by the figs. 1 and 2. In the upper end of this stock is formed an eye, a, to which is attached the draught-rope employed in raising the elevator when in use. Formed in one side of the upper end of the stock A is a longitudinal slot, b, which communicates with the eye a, and consequently with the interior or central slot, c, of the stock, and which has pivoted in it a lever, B, to the upper or outer end of which is secured a suitable tripping-cord, d, and the lower extremity of which is connected by a transverse pin, d', with the upper end of a central rod, C, which extends downward through the internal slot c of the stock, with its lower end pivoted, as shown at b', to the inner ends of two toggle-bars D, the outer ends of which are pivoted to the recessed inner or under sides of two tapering spurs, E, the upper ends of which are pivoted at the two opposite sides, as shown in figs. 1 and 3 of the lower end of the stock A, the said parts being so arranged, that by pushing the rod C downward, the toggle-bars will be forced outward to bring the spurs E into the horizontal position shown in fig. 2, as required in elevating the hay, while, by moving upward the aforesaid rod, the toggle-bars will be brought parallel and into the vertical position indicated in dotted outline in fig. 1, to bring the spurs close together, so that their adjacent pointed ends may pass freely into the mass of hay to be elevated, all as hereinafter further explained. Formed at the upper end of the stock A, one upon each side of the slot b, are two laterally-projecting plates, e, which constitute guards, designed to protect the lever B, when in the position represented in fig. 3, from accidental contact with the beams or timbers of the barn or building in which the elevator is employed.

In using the elevator, the several parts thereof are first brought into the position represented in fig. 1, and the lower end of the same is then forced downward into the mass of hay to be elevated, which being done, the outer arm of the lever B is forced upward into the space between the guards e, which, depressing the inner arm of the aforesaid lever, forces downward the central rod C, and operates the toggle-bars D to force outward the

spurs E, the said toggle-bars being brought nearly or quite in line with each other, in such manner as to brace or sustain the aforesaid spurs in their extended position. The spurs, being thus extended at right angles to the stock A, and embedded in the hay, the elevator is raised in the usual or any suitable manner, by the draught-rope attached to the eye thereof, and the spurs E, catching or holding under the hay surrounding the stock A, sustains the same until it is raised to the required height, whereupon the tripping-cord d is pulled, and, by depressing the outer arm of the lever B, raises the inner arm thereof to draw upwards the inner ends of the toggle-bars in such manner that the weight of the hay upon the spurs E is allowed to force the same downward and inward to their original closed position, the hay being thus allowed to fall from the elevator to the desired place of deposit. Any injury to the lever B, during the elevating-operation just mentioned, from accidental contact with the beams or timbers of the building in which the apparatus is used, is effectually provided against by the guards e, situated at the sides of the said lever, when the same is in position for such elevating-operation, as hereinbefore explained.

What I claim as my invention, and desire to secure by Letters Patent, is—

1. The toggle-bars and central operating-rod, in combination with the tubular stock and the two laterally-moving lifting-spurs, substantially as and for the purpose herein set forth.
2. The arrangement of the guards e with reference to the lever B, and the upper end of the tubular stock A, substantially as and for the purpose herein set forth.
3. The laterally-moving spurs E, toggle-bars D, and central rod e, arranged in relation with the tubular stock A, lever B, and guard e, substantially as and for the purpose herein set forth.

H. A. ESTES.
